UNITED STATES PATENT OFFICE.

ALFRED MOLANDER, OF MINNEAPOLIS, MINNESOTA.

ORE-PULVERIZER.

1,220,257.

Specification of Letters Patent. Patented Mar. 27, 1917.

Application filed March 13, 1916. Serial No. 83,942.

To all whom it may concern:

Be it known that I, ALFRED MOLANDER, of the city of Minneapolis, in the State of Minnesota, United States of America, have 5 invented certain new and useful Improvements in Ore-Pulverizers, of which the following is the specification.

My invention relates to improvements in ore pulverizers and the object of the invention is to devise a simple form of pulverizer which will rapidly and effectually crush ore to any degree of fineness and yet will allow the passage of foreign matter between the crushing members which is too hard to be 15 crushed thereby without damaging the crushing members and in which the wear on the crushing members can be readily taken up and it consists essentially of an outer conical inverted cone-shaped casing open at 20 the top and bottom and having a hopper-like extension formed integral with the open upper end of the conical casing, a base on which the conical casing is secured, a vertical shaft journaled in suitable bearings concentrically within the casing, a conical crushing member secured to the shaft in a concentric position at the bottom and gradually inclined toward the top to an eccentric position, the bottom face of the member being 25 30 inclined upwardly from the side of the cone having the smallest radius at the top toward the side of the cone having the greatest radius, resilient means for supporting the shaft in bearings, means for adjusting the shaft vertically and means for driving the shaft as hereinafter more particularly explained by the following specification.

Figure 1, is a sectional view of my ore pulverizer.

Fig. 2, is a sectional plan view taken on line $x-y$ Fig. 1.

Fig. 3, is a sectional plan view taken on line $x'-y'$ Fig. 1.

In the drawings like letters of reference 45 indicate corresponding parts in each figure.

1 indicates the base upon which is supported an inverted conical casing 2 having an open lower end 3 and an open upper end 4 provided with a hopper-like upward extension 5 into which the ore is fed. 6 indicates standards forming a central vertical bearing 7 located over the center of the casing 2. 8 indicates a slidable bearing block provided with a central step bearing 9 and radially extending arms 10 and 11 slidably fitting at their ends in vertical guides 12

formed in the main base 1. 13 indicates a stationary wedge block formed integral with the main base 1. 14 indicates a slideable wedge block provided with an inclined lower face and a horizontal upper face, the inclined lower face of the wedge block 14 bearing upon the inclined upper face of the wedge block 13. 15 indicates an adjusting screw held within an internally threaded orifice 16 of the base and turnably held in the outer end of the wedge block 14 by suitable means, such as a set screw 17 engaging an annular groove 18 in the screw. 19 indicates a recess formed in the upper end of the step bearing 9. 20 indicates a vertical shaft journaled at its lower end in the step bearing 9 and extending toward its upper end through the vertical bearing 7. The bearing 7 is also provided with a recess 7. 21 indicates a spiral spring fitting in the recess 7 and 22 indicates a spiral spring fitting within the recess 19. 23 indicates a pulley threaded on to the upper end of the shaft 20. 24 indicates a ball bearing inserted between the pulley 23 and spring 21.

It will be noticed that the vertical shaft 20 is mounted concentrically with the center of the casing 3. The casing 3 is provided with a lining 24 preferably formed of manganese steel and corrugated vertically from the top or small end of the conical casing down toward the bottom, such corrugations gradually merging into the circular contour of the inner face of the casing 3.

25 indicates a conical crushing member. The member 25 is provided with an inclined bottom face 26 and the center of the cone is inclined upwardly and outwardly from the center of the casing so that the top of the cone is slightly eccentric to the center of the shaft and casing as clearly indicated in Fig. 2. By this construction the outer edge of the inclined bottom 26 of the conical member extends parallelly with the opposing portion of the inner face of the casing 3.

27 indicates a covering for the conical member 25 also formed of manganese steel, the outer surface of such cover being formed into ratchet-shaped annular projections 28. Each of the ratchet teeth 28 gradually approaches nearer to the inner face of the conical casing as they approach the bottom of the conical member, that is to say, the upper ratchet-shaped tooth portion 28 is farther from the interior face of the casing and the ratchet-shaped portion 28' is closer to the

interior face of the casing with the exception of the lower edge 28² of the cone itself which almost touches the interior face of the casing, and will, therefore, only allow very finely pulverized material to pass therethrough. The interior of the conical member 25 is preferably hollow except at the upper or narrow portion in which is formed a bearing orifice 25^x through which the shaft 20 extends and at the bottom is provided with a central hub 25' and arms 25² extending radially therefrom to the interior face of the member.

In order to keep the central member 25 cool the wall thereof is chambered out at 29. 30 indicates a duct which passes through the radial arm 8 and to the outer end of which is connected a compression air supply pipe. The opposite end of the duct 30 is provided with a vertical portion 31. 32 indicates a duct extending vertically upwardly through the center of the shaft 20 and is provided at its upper end with an angular extension 33. 34 indicates a duct extending through one of the arms 25² and registering at one end with the open end of the duct extension 33 and opening at the opposite end into the chamber portion 29. Air passes through such chamber portions 30 and is exhausted through a duct 35 extending radially inwardly and registering with a similar duct 36 formed in the shaft 20 provided with an upwardly inclined extension 37 leading to the atmosphere. The casing 3 is also similarly chambered out at 38 and provided with a suitable source of supply and exhaust for the compressed air.

Having described the principal parts involved in my invention I will briefly describe the operation of the same.

Ore is fed into the hopper 5 and passes into the space between the interior vertically corrugated face of the conical casing 3 and the exterior face of the cone 26. As the shaft 20 and conical member 26 secured thereto is revolved the eccentric portion of the upper end of the conical member engages with the rock gradually crushing it. The crushed rock passes downwardly through an opening formed between the apex of the ratchet 28^x and the interior face of the casing and is again crushed until it is small enough to pass between the apex of the next tooth in downward succession and the interior of the casing. This process is repeated until the ore is crushed fine enough to pass between the small opening formed between the lower end of the crushing member 28 and the interior face of the casing. If any foreign matter should pass into the pulverizer with the ore such as cannot be crushed by the pulverizer the springs 21 and 22 will allow the crushing member to give and allow the passage of 65 such foreign matter.

If the crushing members wear all that it is necessary to do is to adjust the wedge block 14 by means of the screw 16 so as to raise the member 26 into closer contact with the interior face of the casing 3. When this is done, of course, the pulley 23 and bearing 24 is threaded downwardly into close contact with the spring 21. If it is desired to regulate the fineness to which the ore is crushed this may be done by raising or lowering the crushing member so as to increase or decrease the size of the opening between the lower end of the conical member 26 and the interior of the casing 3.

From this description it will be seen that I have devised a very simple form of pulverizer which will crush ore to any degree desired and which will perform such operation rapidly and efficiently and yet will allow the free passage of any foreign uncrushable matter which may pass accidentally into the pulverizer with the ore and in which the wear may be easily and readily taken up whenever desired.

It will be noted that as the crushing member 25 revolves all the material contained in the space formed by the left hand side of casing 2 and the opposing portion of the crushing member is ground out of that space as that portion of the crushing member passes to the right hand side of the casing by reason of the inclined set of the bottom of the member and the ratchet teeth so that the whole contents of such space is fed downwardly during this turning movement.

What I claim as my invention is:

1. An ore pulverizer comprising an outer inverted conical casing having an open upper and lower end, a vertical shaft journaled in suitable bearings and extending concentrically through the casing and a conical crushing member eccentrically secured to the shaft and having the face of the lower end inclined from one side of the member to the other so that its edge fits freely within the casing by extending parallel with the interior face of the wall of the casing and in close proximity thereto.

2. An ore pulverizer comprising an outer inverted conical casing having an open upper and lower end, a vertical shaft journaled in suitable bearings and extending concentrically through the casing, and a conical crushing member secured to the shaft and having its lower face inclined upwardly from the side of the crushing member having the smaller radius whereby a space is formed by the wall of the crushing member and the casing terminating at its lower end in an acute angle.

3. An ore pulverizer comprising an outer inverted conical casing having an open upper and lower end, a vertical shaft journaled in suitable bearings and extending concentrically through the casing and a conical crush-

- ing member eccentrically secured to the shaft and having the face of the lower end inclined from one side of the member to the other and fitting freely within the casing by 5 extending parallel with the interior face of the wall of the casing, and means for automatically relieving the pressure on the conical member during the feeding out of the crushed material.
- 10 4. An ore pulverizer comprising an outer casing, a vertical shaft, an upper and lower bearing therefor, a crushing member mounted on said shaft, said member including a hollow crushing body portion, and radial 15 arms supporting the base of said portion, and registering ducts in said lower bearing, shaft and arms whereby cooling fluid may be supplied to the interior of said body portion.
- 20 5. An ore pulverizer comprising an outer casing, a vertical shaft, an upper and lower bearing therefor, a crushing member mounted on said shaft, said member including a hollow crushing body portion, registering 25 ducts in said lower bearing, shaft and arms whereby cooling fluid may be supplied to the interior of said body portion, and registering ducts in said upper bearing and shaft for conveying said fluid away.
- 25 6. An ore pulverizer comprising an outer inverted conical casing having an open upper and lower end, a step bearing located below the casing concentrically thereof, a vertical bearing located above the step bearing in vertical alinement therewith, a shaft journaled in the step bearing and vertical bearing, a conical crushing member carried 30
- by the shaft and co-acting with the conical casing, a spiral spring carried by the step bearing on which the crushing member rests, 40 and means for adjusting the step bearing vertically including a wedging element.
7. An ore pulverizer comprising an outer inverted and jacketed conical casing, a vertical shaft journaled in suitable bearings 45 and extending centrally through the casing, a conical crushing member mounted thereon and co-acting with the casing, and means for forcing compressed air under pressure through said bearings and shaft into the interior of the jacket of the casing. 50
8. An ore pulverizer comprising an outer inverted conical casing having an open upper end, a vertical shaft journaled in suitable bearings and extending concentrically 55 through the casing and a conical crushing member eccentrically secured to the shaft and having the face of the lower end inclined from one side of the member to the other, an annular recess formed in and surrounding the periphery of the crushing member parallel with the inclined bottom thereof and forming with the inner face of the casing a triangular pocket having the apex forming the discharge at the bottom 60 and a mouth at the top, and means for automatically relieving the pressure on the conical member during the feeding out of the crushed material from the pocket. 65

ALFRED MOLANDER.
